MEANS FOR SECURING RAILS TO METALLIC TIES.

No. 928,173.

Specification of Letters Patent.

Patented July 13, 1909.

Application filed July 26, 1907. Serial No. 385,754.

To all whom it may concern:

Be it known that we, SAMUEL C. BERRYMAN and JUSTUS C. TURNER, citizens of the United States, and residents of Juniata, Blair county, State of Pennsylvania, have invented certain new and useful Improvements in Means for Securing Rails to Metallic Ties, of which the following is a full, clear, and exact description, reference being had to the accompanying drawings, of which—

Figure 1 is a plan view. Fig. 2 is an elevation, the rail being shown in section. Fig. 3 is a section on the line $x-x$, Fig. 1. Fig. 4 is a section on the line $y-y$, Fig. 1.

This invention relates to improvements in means for securing rails to railroad ties; more particularly to the well known tie of the I-beam form.

20 The object of the invention is to provide a simple and efficient means for clamping the rails to such ties, that will not readily work loose under the strains and jarring of passing trains, and yet that may be readily applied and removed; also to provide such fasteners that may be interchanged from one side of the rail to the other if it be desired to change the gage of the rail a definite distance; as, for instance, around curves 25 when it is necessary to move the outer rail inwardly a fixed amount, to compensate for wear upon the inner side of the head thereof.

To these ends the invention consists in the construction hereinafter described and particularly pointed out in the claims.

Its under surface resting upon the top of the tie, 1, is a plate or clip of metal, 2, having an overhanging portion, 3, between which and the upper surface of the said tie 40 the foot flange of a rail, 4, is adapted to fit and be grasped. Extending downwardly from the under surface of said plate or clip, 2, is a rib, 5, which projects through a slot, 6, in the head of the tie, and whose side abuts 45 against the side of the web, 1^a, of the tie, 1.

The upwardly extending head portion, 7, of a bar, 8 passes through a slot in the edge of the head of the tie, 1, and abuts against one side of the plate or clip, 2, its horizontal 50 limb, 10, extending beneath and contiguous to the under side of the head of said tie, passing through a slot, 11, in the rib, 5, of said plate, and through a slot, 12, in the web of the tie, 1, its free end extending beyond 55 the opposite side of said web. Said free end

of the bar 8 is provided with a vertical slot, 13, in registry with a corresponding vertical slot, 14, through the head of the tie 1, which is in registry with a vertical slot, 15, in the side of the plate or clip, 2. Through these 60 slots, 15, 14, and 13, and frictionally engaging and wedging against the walls thereof, is passed a wedge key, 16, whose lower free end comes against the side of the web, 1^a, of the tie, 1. In order to insure the said wedge 65 key, 16, against vertical displacement, we would preferably spring outwardly the lower end thereof, and provide the same with a slightly in-turned lug, 17, bearing against the web of the tie, as seen in Fig. 4. 70

If the track is to be always maintained at the same gage; that is, the same width or distance between the rails thereof; the walls of the slots, 6, adjacent the rail base would always be substantially in line with the outer edges of said base, and the ribs, 5, of the clips, 2, would be of a length corresponding with said slots. But as it is sometimes desired to change the gage a definite distance, such, for instance, as on curves, when the 80 top of the head of the rail becomes worn away on the inner side, we would preferably so locate the slot 6^a on the outer side of the rail, that its inner wall will be a distance inwardly from the outer edge of the rail foot 8 flange equal to the amount the gage of the track is to be lessened. In consequence of this the rib, 5^a on the clip 2^a on the outer side of the rail would be as much shorter than that of the clip 2 on the inner side, as 90 the distance said gage is to be narrowed. Thus, when it is desired to narrow the gage, as described, all that is necessary to do is to remove the clips and interchange the same so that the inside clip, 2, shall replace the 95 outside clip, 2^a. Whereupon the rail will be moved over until the outer edge of its foot flange or base is in line with the inner wall of the slot, 6^a, thus permitting the longer rib of the clip 2 to be fitted into this slot, and 100 against the rail foot flange.

The inward movement of the rail carries its inner foot flange the same distance beyond the inner edge of the slot, 6 through the tie, on that side so that the shorter rib 5^a 105 of the clip, 2^a will fit the said shortened slot; whereupon the bar, 8, and wedge key, 16 may be replaced to retain the parts in position.

Having thus described our invention, we 110

claim as new and desire to secure by Letters Patent:—

1. Means for securing rails to metallic ties, comprising the rail, the tie supporting the same and having the horizontally disposed head and vertical web, said head being provided with the rib-receiving slots, on opposite sides of the foot flange of the rail, the clips having the rail-engaging portions and 10 having also the downwardly extending ribs projected through said slots, the bars passed through said ribs and tie web contiguous the under surface of said head said bars engaging slots in said head, together with means 15 for retaining said bars in such position, substantially as set forth.
2. Means for securing rails to metallic ties, comprising the rail, the tie supporting the same and having the horizontally disposed head and vertical web, said head being provided with the rib-receiving slots on opposite sides of said web and on opposite sides of the foot flange of the rail, the inner edges of said slots being a predetermined distance 20 apart less than the width of the foot flange of the rail, the clips having the rail-engaging portions, and having also the downwardly extending ribs projected through said slots, the rib of one of said clips being as much 25 longer than the rib of the opposite clip as said distance between said slot edges is less than the rail foot flange, the bars passed through said ribs and tie web contiguous the under surface of said head, together with 30 means for retaining said bars in such position, substantially as set forth.
3. Means for securing rails to metallic ties, comprising the rail, the tie supporting the same and having the horizontally disposed head and vertical web, said head 35

being provided with the rib receiving slots on opposite sides of the foot flange of the rail, the clips having the rail-engaging portions and having also the downwardly extending ribs projected through said slots, the 45 bars passed through said ribs and tie web contiguous the under surface of said head, together with the wedge keys provided with the inturned lugs engaging slots in the clips, substantially as set forth.

4. Means for securing rails to metallic ties, comprising the rail, the tie supporting the same and having the horizontally disposed head and vertical web, said head being provided with the slots therethrough adjacent said web but on opposite sides thereof, the clip having the vertical rib passing through one of said slots, and having also the overhanging rail-engaging portion, the 55 said rib of said clip and the web of the tie being provided with aligned horizontal slots, the bar, a limb of which is passed through said aligned slots and is provided, adjacent one end, with a vertical through slot in alignment with the other vertical through slot in said tie head, and with a vertical slot in the side of said clip; the wedge key passed through said aligned vertical slots and securing the tie and bar together, said bar at its 60 opposite end being provided with an upwardly extending portion engaging a vertical slot through said tie head, substantially as and for the purpose set forth.

In testimony whereof, we have hereunto affixed our signatures.

SAMUEL C. BERRYMAN.
JUSTUS C. TURNER.
